UNITED STATES PATENT OFFICE.

THEOPHILUS BROWN, OF MOLINE, ILLINOIS, ASSIGNOR TO THE MARSEILLES COMPANY, OF EAST MOLINE, ILLINOIS, A CORPORATION OF ILLINOIS.

CONVEYER-CHUTE.

1,256,515.

Specification of Letters Patent. Patented Feb. 19, 1918.

Application filed June 20, 1916. Serial No. 104,761.

To all whom it may concern:

Be it known that I, THEOPHILUS BROWN, a citizen of the United States, residing at Moline, in the county of Rock Island and State of Illinois, have invented certain new and useful Improvements in Conveyer-Chutes, of which the following is a specification, reference being had therein to the accompanying drawing.

10 My invention relates to conveyer chutes, particularly to that class in which the chute is formed of sections movably connected together in such a manner that the chute can be readily telescoped to adjust it to varying 15 lengths or for purposes of storage or transportation, and the object of my invention is to simplify the operation and economize the cost of construction.

Referring to the drawings in which similar numerals indicate identical parts—

Figure 1 is a plan view embodying my improvements.

Fig. 2 is a side elevation of Fig. 1.

Fig. 3 is a part view in perspective, and

25 Fig. 4 is a detail.

Although it is obvious that as many sections may be used as desired, I have shown a chute composed of only four sections, 1, 2, 3 and 4; each section is constructed of sheet 30 metal bent to a curve and having tubular parallel edges 5. Section 1 is the receiving end of the chute and has its rear end secured to a member 6, stiffening the end of the section to support a hopper 7 which is pivotally se-

35 cured thereon by bolts 8 which extend through the member 6, the sides of the section 1, and the hopper 7. The rear end of each section is secured to an annular member 9 within which the end of the section is in-

40 closed and to which it is rigidly secured in any suitable manner.

The sections increase in size and fit one within the other from 1 to 4, and are readily movable longitudinally to telescope the 45 chute.

To reinforce the sections and to prevent any tendency to rotate, I insert in the tubular edges 5 of each section a rod which is bent to form an arch 10 at the forward end 50 of its respective section and has its free ends 11 projecting from the tubular edges and

bent inwardly and downwardly to form hooks to overlap the edges of the adjacent section as shown, forming guides which not only prevent each section from a rotary 55 movement, but serve to retain the position of the sections in proper relation to each other when they are moved longitudinally. To limit the longitudinal movement of the sections in extending the chute, I provide 60 chains 12 which are connected to rings 13, secured to the rings 9 on the rear ends of the sections, except the rearward chain which is connected to the ring 13 on the ring 9 of section 2 and to the member 6 on the rear 65 of section 1. By using chains of greater or lesser length it is obvious the chute can be extended or contracted longitudinally to suit the conditions governing its use.

What I claim is—

70 1. An open chute comprising sections adapted to be adjusted longitudinally one within the other and having longitudinal tubular edges, and a rod extended through the tubular edges of each section and forming a brace extending across one end thereof, the free ends of said rod projecting from the opposite end of said tubular edges and bent to slidably engage with the edges of the next adjacent section. 75

80 2. An open chute comprising sections adapted to be adjusted longitudinally one within the other and having longitudinal tubular edges, and a rod extended through the tubular edges of each section and forming an arched brace extending across one end thereof, the free ends of said rod projecting from the opposite end of said tubular edges and bent inwardly and downwardly to slidably engage with the edges of the next 90 adjacent section. 85

85 3. An open chute comprising sections adapted to be adjusted longitudinally one within the other, a brace at one end of each section and extending transversely thereof, 95 an annular member at the opposite end of each section and to which the respective section is secured, and means on each section adjacent the annular member to slidably engage with the edges of the adjacent section. 100

4. An open chute comprising sections

adapted to be adjusted longitudinally one within the other and having longitudinal tubular edges, an annular member secured to one end of each section, and a rod extended through the tubular edges of each section and having its ends bent inwardly and downwardly adjacent the annular member to slidably overlap the edges of the adjacent section, said rod forming an arched

brace extending transversely of each section 10 at the end opposite to the annular member.

In testimony whereof I affix my signature, in presence of two witnesses.

THEOPHILUS BROWN.
